COUNTERWEIGHT CONTROL SYSTEM FOR
LIFTING DEVICE CARRIAGESPierre Jean-Marie Theodore Allard, Chantilly,
France; vested in the Alien Property Custo-
dianApplication February 1, 1943, Serial No. 474,326
In France March 11, 1941

10 Claims. (Cl. 212—84)

My invention relates to lifting devices of the type including a horizontal or slightly inclined guideway along which a carriage is adapted to run, to which crab is hung an automatic grab or like goods-handling device, said carriage advancing in a given direction under the action of a counterweight adapted to return the carriage towards the discharging position. The invention is more particularly applicable to the apparatuses of the type described in my prior specification Ser. No. 282,817, filed on July 4, 1939, now Patent No. 2,270,916, granted January 27, 1942.

Said invention has for its object a counterweight control system for returning the carriage towards the discharging position and adapted to stop the carriage at a predetermined point of its return travel. To this end, according to the invention, an adjustably positioned stop is arranged in the path of the counterweight so as to balance the action of the latter and to stop the carriage at the desired point.

In the case of an automatic grab of the type described in the above mentioned prior specification, this stopping of the carriage produces at the same moment the automatic emptying of the grab through the slack given to the lifting cable to which the grab is suspended.

Other features of the invention will appear from the following description, reference being made to the accompanying drawing in which:

Fig. 1 is a diagrammatic view of a first form of the invention.

Fig. 2 shows diagrammatically a modified form of counterweight stop, said stop being actuated by an electromagnetic relay.

Fig. 2A is an elevation showing a plurality of stops such as shown in Fig. 2 in combination with a suspended counterweight.

Fig. 3 shows another modified form of counterweight stop, including a single stop adjustably positioned as to height.

Fig. 4 shows diagrammatically an automatic device for giving the stop a reciprocating vertical motion at a uniform or variable speed so as to produce a regular or irregular displacement of the point at which the grab or the like part empties its contents between two extreme points corresponding to the extremities of the path allowed for the adjustable stop.

Referring to the drawing, 1 designates an automatic grab, secured to the end of a hoisting cable 2 passing over a return pulley 3 carried by a carriage or trolley 4, the rollers 5 of said trolley running along a horizontal or slightly inclined rail 6. The opening ring 7 is suspended by a cable

arranged in the same longitudinal vertical plane as the cable 2. A lever 8 is pivotally secured as at 9 to the carriage 4, said lever being provided with a counterweight or a spring 10 for urging brake shoe 36 into contact with the rail or guideway 6.

When in position for loading over the axis AB, the carriage abuts against the stop 11 under the action of the weight of the grab suspended to the cable 2.

The carriage is urged to the right in Fig. 1 by the return system, including a cable 12 passing over a return pulley 13 and to the end of which is suspended a driving counterweight 14.

In the form of execution of Fig. 1, a rotary rod 15 is arranged parallel to the path of the counterweight 14. Rod 15 is provided at different heights with fingers 16, 17, 18, which fingers project radially at different angles from the rod and serve as stops when moved into the path of the counterweight. Rod 15 is mounted in bearings 15a and 15b attached to a stationary object 20. The rod 15 carries also a lever 19 whereby it is possible to give said rod the desired angular position. The lowermost stop may be constituted by a stationary part 20.

According to the angular position given to the rod 15, the counterweight is arrested by either of the stops constituted by a finger 16, 17 or 18 or the part 20, so as to stop the grab in the corresponding emptying position, as shown diagrammatically at a, b, c and d.

In the form of execution illustrated in Figs. 2 and 2A, 21 designates one of the stops distributed at different heights along the path of the counterweight 16. This stop is carried by a lever 22 adapted to pivot round a stationary axis 23, said stop being urged in one direction by a spring 24 and in the opposite direction by the armature 25 of a coil 26. Coil 26 is inserted in the circuit of a current supply 27, which circuit has a switch 28. Normally, the switch 28 being open, the spring 24 urges the lever 22 into the position shown in dot and dash lines, for which the stop 21 is no longer in the path of the counterweight 14. When the switch 28 is closed, the coil 26 attracts its armature 25 which, in turn, brings the stop 21 back into the path of the counterweight.

50 The stops 21 oscillate back and forth in slots 21a provided in stationary member 21b. When the stop is in the position shown in the upper portion of Fig. 2A, the descending counterweight 14 will not strike the same, but when the stop occupies the lowermost position, it is disposed in

the vertical groove 21c in which the counterweight travels, and therefore the stop will block the downward movement of the counterweight.

In the example shown in Fig. 3, the stop 29 which stands constantly in the path of the counterweight 14, is constituted by a plate adjustably positioned as to height. To this end, the plate 29 is secured to a screw 30, screwed inside a nut 31, said nut being held horizontally stationary by any suitable means, while a guiding rod 32 cooperates with the plate 29 in order to prevent the screw from rotating. By rotating the nut 31 by means of a crank 31b and worm 31a, or the like, there is provided a vertical displacement of the plate 29.

In the modification according to Fig. 4, the plate 29 or a contact moving integrally therewith, may engage the contacts 33, 33a of a reversing switch 34 inserted in the circuit leads r , s , t , r' , and s' of a motor 35, which motor controls the rotation of the nut 31. As the motor is constantly rotating, either in one direction or in the other according to the position of the reversing switch 34, the plate 29 moves at a uniform speed between the two contacts 33, 33a, alternatingly upwards and downwards. Consequently the point where the counterweight is stopped during its successive travels varies for each travel of the grab in a regular manner. Thus the grab is emptied to form a uniform heap between two extreme emptying points (say a and b) the position of which depends on that of the contacts 33, 33a.

Of course, the invention is by no means limited to the examples of execution described hereinabove, which are given solely by way of example and it is obvious that many mechanical, electrical, hydraulic or the like devices may be readily imagined for varying the position of the stops for the counterweight 14, either at will or automatically.

Having now described my invention what I claim as new and desire to secure by Letters Patent is:

1. In a lifting device including a substantially horizontal guideway, a grab, a carriage carrying said grab and adapted to move along the guideway between loading and discharging positions, a counterweight adapted to return the grab towards discharging position, the provision of movable abutment means for the counterweight to relieve the carriage from the action of said counterweight and rotary means for positioning said abutment means into the path of the counterweight at a desired predetermined point of said path.

2. In a lifting device including a substantially horizontal guideway, a grab, a carriage carrying said grab and adapted to move along the guideway between loading and discharging positions, a counterweight adapted to return the grab towards discharging position, the provision of a plurality of separate stops distributed along a line close to the path of the counterweight, and rotary means for bringing selectively one of said stops into the path of the counterweight for stopping same at the corresponding point of its path.

3. In a lifting device including a substantially horizontal guideway, a grab, a carriage carrying said grab and adapted to move along the guideway between loading and discharging positions, a counterweight adapted to return the grab towards discharging position, the provision of a plurality of separate stops distributed along a line close to the path of the counterweight, rotary means individual to each stop for bringing selectively said stops into the path of the counterweight for stopping same at the corresponding point of its path.

4. In a lifting device including a substantially horizontal guideway, a grab, a carriage carrying said grab and adapted to move along the guideway between loading and discharging positions, a counterweight adapted to return the grab towards discharging position, the provision of a rod arranged parallel to the path of the counterweight, a plurality of separate stops carried by said rod at different points of its length and projecting radially therefrom along different angular directions and means for rotating said rod for bringing selectively one of the stops into the path of the counterweight.

5. In a lifting device including a substantially horizontal guideway, a grab, a carriage carrying said grab and adapted to move along the guideway between loading and discharging positions, a counterweight adapted to return the grab towards discharging position, the provision of a plurality of separate stops distributed along a line close to the path of the counterweight and separate means for projecting the different stops into the path of the counterweight and separate means for retracting the different stops out of said path.

6. In a lifting device including a substantially horizontal guideway, a grab, a carriage carrying said grab and adapted to move along the guideway between loading and discharging positions, a counterweight adapted to return the grab towards discharging position, the provision of a plurality of separate stops distributed along a line close to the path of the counterweight and electromagnetic separate means for projecting the different stops into the path of the counterweight and retracting same out of said path.

7. In a lifting device including a substantially horizontal guideway, a grab, a carriage carrying said grab and adapted to move along the guideway between loading and discharging positions, a counterweight adapted to return the grab towards the discharging position, the provision of a plurality of separate stops distributed along a line close to the path of the counterweight and abutment means operatively associated with said counterweight, and means for moving said abutment means to a plurality of obstructing positions in the path of said counterweight.

8. In a lifting device including a substantially horizontal guideway, a grab, a carriage carrying said grab and adapted to move along the guideway between loading and discharging positions, a counterweight adapted to return the grab towards discharging position, the provision of a threaded rod arranged close to the path of the counterweight, a stop carried by said rod and projecting into said path, a nut threadably secured upon the rod and controlling the longitudinal position of the rod, means for preventing displacement of the nut longitudinally of the rod, means for rotating the nut and means for preventing rotation of the rod.

9. In a lifting device including a substantially horizontal guideway, a grab, a carriage carrying said grab and adapted to move along the guideway between loading and discharging positions, a counterweight adapted to return the grab towards discharging position, the provision of a threaded rod arranged close to the path of the counterweight, a stop carried by said rod and projecting into said path, a nut fitted over the rod and controlling the longitudinal position of the rod, means for preventing displacement of the nut longitudinally of the rod means for prevent-

ing rotation of the rod, a motor constantly rotating the nut, and means controlled by the stop at two points of its travel for reversing the direction of rotation imparted to the nut.

10. In a lifting device including a substantially horizontal guideway, a grab, a carriage carrying said grab and adapted to move along the guideway between loading and discharging positions,

a descending counterweight for returning the grab towards the discharging position, abutment means for stopping said descending counterweight, and means for adjustably moving said abutment means along the path of the counterweight to different obstructing positions.
